self explanatory not being reproduced hereover and particularly gathering thereof all merit views same as heretofore published in heretofore issued patent application Serial No. 31,000,000 filed on December 10, 1946, now of record, and which application is assigned to the assignee of this application.

UNITED STATES PATENT OFFICE

Filed on December 10, 1946, to record application.

Patented June 15, 1948. Serial No. 2,443,231.

WINDING MECHANISM

William J. Elvin, Frostburg, Md., and Elmer R. Stahl, Meyersdale, Pa., assignors to Celanese Corporation of America, a corporation of Delaware.

Application January 17, 1947, Serial No. 722,638.

6 Claims. (Cl. 57—76)

1

This invention relates to a yarn take-up device comprising a take-up bucket or Topham box and relates more particularly to improved yarn traverse means for the take-up device.

An object of this invention is to provide improved mechanism for traversing yarn in a take-up bucket or Topham box.

Another object of this invention is to provide improved mechanism for traversing yarn in a take-up bucket or Topham box smoothly and evenly and at unusually high speeds.

Still another object of this invention is to provide yarn traversing means for a take-up bucket or Topham box wherein the traverse stroke is not only adjustable but may also be varied even while the yarn traversing means is in operation.

A further object of this invention is the provision of yarn traversing means for a take-up bucket or Topham box which may be swung clear of the take-up bucket or Topham box when the latter is full so as to permit ready removal of the yarn cake formed without disturbing the precise adjustment of the traverse stroke.

Other objects of this invention will appear from the following detailed description and the accompanying drawing.

In the drawing.

Fig. 1 is a schematic, side-elevational view of a yarn stretching device, showing yarn take-up buckets wherein the novel yarn traversing means of our invention may be employed.

Fig. 2 is a perspective view, partly broken away, of our novel yarn traversing mechanism in operative position over a take-up bucket.

Fig. 3 is a detail of a locking mechanism which is provided for locking the novel yarn traversing means in operative position.

Fig. 4 is a side-elevational view of the novel yarn traversing mechanism at the base of the normal traverse stroke.

Fig. 5 is a side-elevational view of the novel yarn traversing mechanism at the top of the normal traverse stroke, and

Fig. 6 is a side-elevational view of our novel yarn traversing mechanism showing the locking mechanism disengaged to allow the traversing means to be swung clear of the take-up bucket so as to permit discharge of the yarn cake formed therein.

Like reference numerals indicate like parts throughout the several views in the drawing.

Referring now to the drawings and particularly to Fig. 1, a plurality of yarns 10 are drawn from a creel 11, passed into a wetting-out bath 12 and then led into a steam stretching unit,

described as being in the steam bath and left there 13 and converted to stretchable and no twist holding a no breakage in the fiber of the fiber roving (wool or fiber) subject with oxygen and subject to heat at a temperature sufficient to cause the fiber to become soft and pliable, and then to subject the fiber to a high speed of stretching and to have the fiber elongated and made soft by being stretched rapidly.

2

generally indicated by reference numeral 13, where they are softened by being subjected to the action of hot water or steam under pressure. The softened yarns are then stretched to any

5 desired degree by suitable stretch rollers 14, 15 and 16, respectively operating at the necessary speed differentials to impart the desired stretch. Each of the stretched yarns 10 is led over a roller 17 where a suitable lubricant or conditioning agent is applied and then each individual yarn is wound a number of times about a separate godet wheel 18 rotated by a driven shaft 19 and then over a guide rod 20 which acts to keep the several yarn windings separated as the yarn is advanced along said godet wheel.

10 The yarn 10 is passed through a funnel yarn guide 21 while still in a wet condition and is thus led into a yarn take-up bucket 22 which is normally rotated at high speed by an electric motor

15 23 carried on a suitable support 24. The motor is provided with a drive shaft or spindle 25 which frictionally engages bucket 22 and is connected to a suitable source of power by means of leads 26.

20 The centrifugal force exerted on yarn 10 by the rotation of take-up bucket 22 at high speed causes said yarn to be thrown outwardly against the inner surface of the take-up bucket 22 and to be held there by centrifugal force, as the windings build up, in the form of a yarn cake 27.

25 The even distribution of the yarn windings to form cake 27 is effected by the traversing action of funnel yarn guide 21 which is mounted on a vertically reciprocating traverse bar 28 by means

30 of a suitable supporting arrangement generally indicated by reference numeral 29. The supporting arrangement comprises a threaded bushing 30 in frictional engagement with funnel yarn guide 21 and provided with a knurled grip or handle 31 for convenient adjustment. Bushing

35 is mounted on a horizontal plate 32 and may be held in any vertically adjustable position therein by means of a pair of knurled lock nuts 33.

40 The vertical reciprocation of traverse bar 28 and the funnel yarn guide mounted thereon, is produced by the action of a uniform motion, heart-shaped cam 34 keyed to a rotating shaft

35 which is driven at any desired speed by suitable means (not shown). A spring 36 is provided to maintain the periphery of cam 34 in constant contact with traverse bar 28, the point of contact being a cam follower 37 which is rotatably mounted on a pin 38 carried in a bracket

45 39 attached to the under surface of traverse bar

50 39 attached to the under surface of traverse bar

28. One end of spring 36 is fixed to a bracket 40 on the underside of traverse bar 28 and the other to a bracket 41 mounted on a portion 42 of the main supporting frame (not shown) which carries the entire traverse mechanism. As cam 34 rotates it forces traverse bar 28 upward against the tension of spring 36 and, after the peak of cam 34 passes cam follower 37, traverse bar 28 is drawn down by the tension of spring 36.

Guide rods 43 and 44 are provided to keep the reciprocating yarn guide 21 and guide bracket assembly 29 in perfect alignment during the yarn winding or cake-building operation, guide rod 43 being round and guide rod 44 being square in cross-section. Both of said rods may be integral with a normally stationary U-shaped platform bracket 45. Rod 43 is provided with a guide sleeve 46 fixed to plate 32. Rod 44 is not provided with a sleeve but merely slides in a square guide hole 47 machined in plate 32 which acts as a bearing. Traverse bar 28 is pivotally attached to plate 32 by means of a bracket 48 having a bolt 49 passing through said bracket and providing a pivot for traverse bar 28. Bolt 49 is held in position by a nut 50.

The fulcrum of reciprocating traverse bar 28 is part of a shackle arrangement, generally indicated by reference numeral 51 which is designed to cause funnel yarn guide 21 to reciprocate in a vertical path which is tangent to the normally arcuate path the yarn guide 21 would describe if not compensated for by the shackle arrangement 51. The shackle arrangement comprises a pair of links 52 pivotally attached at their lower extremity by pins 53 to a bracket 54 mounted on an internally drilled and threaded block 55. Block 55 rides on a pair of cylindrical guide rods 56 which are attached to a bracket 57 by means of nuts 58. Block 55 may be shifted forward or backward to effect any necessary or desirable adjustments in the length of the stroke of traverse bar 28 by suitably rotating a threaded rod or worm 59 which passes through block 55. A crank handle 60 is provided at one end of threaded rod 59 rotating freely in a bearing 61 set in bracket 57. Additional traverse adjustment means are provided at the end of traverse bar 28, said means comprising a sliding block 62 pivotally attached by a pin 63 to links 52, and sliding in a rectangular frame 64 attached to the end of traverse bar 28. Block 62 may be moved forward or backward inside the frame 64 through the action of a crank 65 which is keyed to the end of a threaded rod or worm 66 passing through block 62 and rotating in a hole 67 in frame 64 which acts as a bearing for the end of worm 66.

When the cake building operation has proceeded for a sufficient period of time to build a yarn cake 27 of the desired size, take-up bucket 22 containing the cake 27, is removed and is replaced by an empty bucket so that the yarn take-up may be continued. To do this, the traversing of bar 28 is first halted by disengaging the drive mechanism (not shown) rotating shaft 35 and cam 34, and the funnel yarn guide 21 and bracket assembly 29 are swung clear as shown in Fig. 6. Cover 68 of a box 69, which is adapted to contain any spray thrown off by the rotating buckets is then lifted clear and take-up bucket 22 may then be withdrawn from motor spindle 25 and an empty bucket substituted.

In order to enable the funnel yarn guide 21 and the bracket assembly 29 to be swung a sufficient distance away to permit cover 68 to be lifted clear of the box 69, means are provided for disengaging

the traverse mechanism and for swinging the same away from its normal traversing position. Such means comprises a stationary bracket 70 fixed to box 69 and the U-shaped platform bracket 45 which is connected to bracket 70 by means of a parallel motion links 71 and 72. During the normal traverse stroke platform bracket 45 is held in contact with the stationary bracket 70 by means of a latch 73 which is fixed to said bracket and engages a rod 74 set in platform bracket 45. Latch 73 is spring-loaded by means of a spring 75. The force of said spring may be counteracted to permit latch 73 to be disengaged from rod 74 by rocking a handle 76 in a counter-clockwise direction. Handle 76 is connected to an eccentric bushing 77 and the movement of handle 76 in a counter-clockwise direction rotates bushing 77 sufficiently to permit a spring guide pin or shoulder 78 on which eccentric bushing 77 bears to be pressed thereby to the left, releasing the spring pressure sufficiently to allow latch 73 to be disengaged from rod 74. Upon release of latch 73, as shown in Fig. 6, the whole traverse bar assembly and yarn guide 21 rocks on parallel motion links 71 and 72 as well as on links 52 so that it is drawn upward and backward. This movement permits cover 68 to be removed and the loaded take-up bucket 22 to be lifted out and replaced by an empty bucket. The yarn winding may be resumed by forcing traverse bar 28 and the yarn guide assembly downward, locking latch 73 on bar 74 by rocking handle 76 in a clockwise direction and dropping yarn 10 through funnel yarn guide 21 a sufficient distance so that it will be caught up by the take-up bucket 22 and wound into a yarn cake 27.

40
45

70
75

The advantage of our novel traverse mechanism lies in the fact that once the traverse stroke of funnel yarn guide 21 has been adjusted as desired by rotating cranks 60 and 65, the yarn take-up bucket 22 may be filled and removed continuously through disengagement of latch 73 without any necessity for readjusting the traverse stroke of the yarn guide 21 at each discharging operation.

It is to be understood that the foregoing detailed description is given merely by way of illustration and that many variations may be made therein without departing from the spirit of our invention.

Having described our invention, what we desire to secure by Letters Patent is:

1. In a yarn traversing device for building a yarn cake in a yarn take-up bucket, the combination with a yarn guide directing a yarn into a rotating take-up bucket, of traversing means for vertically reciprocating the yarn guide including a pivotally mounted traverse bar carrying said yarn guide at the free end thereof and a rotating cam in contact therewith, locking means for detachably securing said yarn guide and traverse bar in operative position, and means operatively connected to said traverse bar for varying the effective length of said traverse bar so as to vary the vertical stroke of said yarn guide.

2. In a yarn traversing device for building a yarn cake in a yarn take-up bucket, the combination with a yarn guide directing a yarn into a rotating take-up bucket, of traversing means for vertically reciprocating the yarn guide including a pivotally mounted traverse bar carrying said yarn guide at the free end thereof and a rotating cam in contact therewith, locking means for detachably securing said yarn guide and traverse

bar in operative position, and means at the fulcrum end of said traverse bar for varying the effective length of said traverse bar so as to vary the vertical stroke of said yarn guide.

3. In a yarn traversing device for building a yarn cake in a yarn take-up bucket, the combination with a yarn guide directing a yarn into a rotating take-up bucket, of traversing means for vertically reciprocating the yarn guide including a pivotally mounted, traverse bar carrying said yarn guide at the free end thereof, a rotating cam in contact with the underside of the traverse bar for raising said traverse bar on the upward stroke, spring means cooperating with said traverse bar for effecting the downward stroke, locking means for detachably securing said yarn guide and traverse bar in operative position, and means at the fulcrum end of said traverse bar for varying the effective length of said traverse bar so as to vary the vertical stroke of said yarn guide.

4. In a yarn traversing device for building a yarn cake in a yarn take-up bucket, the combination with a yarn guide directing a yarn into a rotating take-up bucket, of traversing means for vertically reciprocating the yarn guide including a pivotally mounted traverse bar carrying said yarn guide at the free end thereof, a rotating cam in contact with the underside of the traverse bar for raising said traverse bar on the upward stroke, spring means cooperating with said traverse bar for effecting the downward stroke, locking means including a spring-loaded latch for detachably securing said yarn guide and traverse bar in operative position, and means at the fulcrum end of said traverse bar for varying the vertical stroke of said yarn guide.

5. In a yarn traversing device for building a yarn cake in a yarn take-up bucket, the combination with a yarn guide directing a yarn into a rotating take-up bucket, of traversing means for vertically reciprocating the yarn guide including a pivotally mounted traverse bar carrying said yarn guide at the free end thereof, a rotating cam in contact with the underside of the traverse bar for raising said traverse bar on the upward stroke, spring means cooperating with said traverse bar for effecting the downward stroke, locking means including a spring-loaded

latch for detachably securing said yarn guide and traverse bar in operative position, and means at the fulcrum end of said traverse bar including pivotally mounted links connecting a sliding block having a rotatable worm in said block with a second worm-operated sliding block disposed below the first mentioned sliding block, for varying the stroke of said yarn guide.

6. In a yarn traversing device for building a yarn cake in a yarn take-up bucket, the combination with a yarn guide directing a yarn into a rotating take-up bucket, of traversing means for vertically reciprocating the yarn guide including a pivotally mounted traverse bar carrying said yarn guide at the free end thereof, a rotating cam in contact with the underside of the traverse bar for raising said traverse bar on the upward stroke, spring means cooperating with said traverse bar for effecting the downward stroke, locking means including a fixed bracket carrying a spring-loaded latch, a pivotally mounted bracket linked to said fixed bracket having said yarn guide mounted thereon and said traverse bar pivotally attached thereto, means on said pivotally mounted bracket cooperating with said spring-loaded latch for detachably securing said bracket, yarn guide and traverse bar in operative position, and means at the fulcrum end of said traverse bar including pivotally mounted links connecting a sliding block having a rotatable worm in said block with a second worm-operated, sliding block disposed below the first mentioned sliding block for varying the vertical stroke of said yarn guide.
